UNITED STATES PATENT OFFICE.

WALTER C. KELSO, OF BELLEVUE, IOWA.

SHIPPING-CRATE.

1,323,534.

Specification of Letters Patent.

Patented Dec. 2, 1919.

Application filed March 20, 1918. Serial No. 223,546.

To all whom it may concern:

Be it known that I, WALTER C. KELSO, a citizen of the United States of America, residing at Bellevue, in the county of Jackson and State of Iowa, have invented certain new and useful Improvements in Shipping-Crates, of which the following is a full, clear, and exact description.

My invention relates to shipping crates, with special reference to such as are called collapsible, and the object is to provide a crate that shall be very strong, moderately light in weight, not bulky in form, well ventilated, may readily be rolled into a small, compact bundle with no unused space, the heads removable, can be rolled and handled as a barrel and if any part be broken or lost it may be readily replaced without disturbing the balance of the crate and can be constructed with very small cost.

In the following specification and drawings accompanying the same and forming a part hereof, will be fully described and illustrated its manner of construction and mode of operation and how used.

Figure 1 is a perspective view of the crate complete.

Fig. 2 is a side view of one of the staves with reinforcement by strips.

Fig. 3 is a side view of a portion of a hoop.

Fig. 4 is a cross section of the central or locking stave with one of the contiguous staves on each side and a side view of the hoop.

Fig. 5 is a side view of the locking stave.

Fig. 6 is an end view of the crate in condition to be filled and also an end view of a form for holding the crate while being filled.

Fig. 7 is an end view of one of the heads.

Fig. 8 is a side view of the supporting post with a section of the head.

Like characters of reference denote corresponding parts in each of the figures.

Having reference to the drawings 2 represents the crate, which is preferably of barrel shape, and 4 the staves comprising the crate, which staves are preferably composed of straight pieces of substantially the same length and width and are set lengthwise of the crate. At each end of the staves is secured a block 5 for retaining the heads in position, when the crate is filled. The outer side of each stave is reinforced by a strip 6 of substantially the same width as the stave but only extending a part of the length of

the stave along its central portion. The purpose of which is not only to reinforce the stave but also, when the crate is rolled along or handled, its direction can be readily changed.

For the purpose of preventing the heads from falling in and for further strengthening the same, there are provided four posts 7 which have the same reinforcements as the staves. They are also provided with the same blocks 5. They are also thickened by which they provide four square shoulders on which the heads 32 may firmly rest. With some kinds of goods these posts are not a necessity.

The staves 4 are secured to hoops or bands 8 by staples 10, which hoops encircle the crate in substantially horizontal planes when the crate stands on one end. The ends 75 of the hoops 8 are formed into loops, for the purposes presently to appear.

The crate may be further reinforced by staves 15 and 16, which are also fastened to the staves, one end of one stay is fastened 80 to the stave 18 near the top and the other end to the stave 20 near the bottom, and the other stay secured to the stave 20 near the top and the other end to the stave 18 near the bottom, and these stays run diagonally around the crate.

In order to unite the staves after they are attached to the hoops 8 and stays 15 and 16, and to form them into a barrel shape, and lock them together, there is provided a key 90 25, shown in Fig. 5 and preferably made in three parts 26, 28 and 30. The strip or part 28 is provided with a hole 29, into which may be inserted the end of a rod or bolt so that the strokes of a hammer may drive the part 28 upward and outward. The strip 26 consists of a thin strip of wood or metal of substantially the same size throughout, the other two pieces 28 and 30 may be of wedge shape and formed by cutting lengthwise a 100 rectangular piece diagonally. The size may vary according to the space to be locked.

The heads 32 are preferably made of woven wire 34 or of strips of wood fastened at right angles to each other as shown in 105 Figs. 6 and 7. The ends of these strips fit interiorly of the blocks 5 on the ends of the staves. In case the four posts 7 are used, the heads 32 rest upon the thickened portions of the posts 7. In such case, the heads have four recesses 13 cut in their edges and set the same distance apart to accommodate

a number of heads for return shipment and other purposes as will hereinafter appear.

Around the ends of the strips or the ends of the wire composing the head is secured a 5 rim 40, which may be made very cheaply of refuse pieces of wood, securely fastened together and to the strips of the head.

The manner of assembling and using is substantially as follows: starting with the 10 hoops 8 and stays 15 and 16 fastened to the staves, the operator brings the staves 18 and 20 together into barrel shape and inserts through the loops of the hoops the thin strip 26 and the wedge strip 30, then inserts 15 the heads in their position beneath the blocks 5 and on top of the enlarged portions of the posts 7, and then drives the wedged shaped piece 28 between the strips 26 and 30, locking and completing the crate.

20 When it is to be filled, the operator places the crate in the form, shown in Fig. 6 and unlocks the crate and turns back a portion of the staves on both sides over the upper edge of the form. After filling the crate he 25 brings the staves together over the contents and locks the crate as set out before.

Upon receiving the filled crate, the heads or either head may be released by simply inserting a punch in the hole 29 of the wedge 30 28 and driving it out. The heads may then be removed. In making the return shipment after the contents has been removed, all the crates may be laid out flat, one upon another and then rolled up with locking 35 staves inside, or rolled into a bundle. The heads may be packed into a crate with the posts 7 fitting into the recesses 13, and the

staves rolled around the crate, or in any other convenient manner.

It will be seen by this mode of construction, that the crate will be exceedingly strong, easily made and with very little cost, and very little expense for returning the 40 crate for future shipment.

Having now described my invention what 45 I claim is:—

1. A crate including staves, hoops connected to the staves and having terminal loops, and a series of coöperating and removable strips engaging all of said loops, 50 certain of said strips being of wedge formation.

2. A crate including staves, hoops connected with the respective staves and having terminal loops adapted to align when the 55 staves are in crate forming relation, and a locking member to engage all of said loops and comprising spaced sections one of which has a wedge formed edge, and an intermediate wedge section to be forced between 60 said spaced sections.

3. A crate including a series of staves, reinforcing strips secured to the outer edges of the staves, hoops connected to said reinforcing strips and terminating in loops, and 65 a locking member made up of separable strips to engage all of said loops.

In testimony whereof I have affixed my signature in presence of two witnesses.

WALTER C. KELSO.
